UNITED STATES PATENT OFFICE

ERNEST E. LINDSEY, OF SAN FRANCISCO, CALIFORNIA

DESIGN FOR A COUNTER CONFECTION FREEZER

Application filed January 3, 1933. Serial No. 46,685. Term of patent 14 years.

To all whom it may concern:

Be it known that I, ERNEST E. LINDSEY, a citizen of the United States of America, and resident of the city and county of San Francisco, State of California, have invented a new, original, and ornamental Design for a Counter Confection Freezer, of which the following is a specification, reference being had to the accompanying drawing, forming part thereof.

I claim:

The ornamental design for a counter confection freezer, as shown.

In testimony whereof, I have hereunto set my hand.

ERNEST E. LINDSEY.
